[57] **CLAIM**

The ornamental design for storm water outlet, as shown.

DESCRIPTION

FIG. 1 is an isometric view of a storm water outlet showing our new design;

FIG. 2 is a front elevation thereof;

FIG. 3 is a rear elevation thereof;

FIG. 4 is an elevation taken from one side thereof;

FIG. 5 is an elevation taken from the side opposite that shown in FIG. 4;

FIG. 6 is a top plan view thereof; and

FIG. 7 is a bottom plan view thereof.

FIG.1

FIG.2

FIG.3

FIG. 4

FIG. 5

FIG. 6

FIG. 7
